UNITED STATES PATENT OFFICE

FRANK L. YERGES, OF FREMONT, OHIO; AMELIA N. YERGES, EXECUTRIX OF SAID
FRANK L. YERGES, DECEASED, ASSIGNOR TO THE YERGES MANUFACTURING COM-
PANY, OF FREMONT, OHIO, A CORPORATION OF OHIO

BUFFING OPERATION

Application filed January 4, 1926. Serial No. 79,203.

This invention relates to fabric buffers of the warp and woof type wherein there is impregnation thereof with substance which decreases tendency for the fabric to fray, 5 while there may be a material increase in the quantity of work which may be performed with said buffer before wearing out.

This invention has utility when incorporated in fireproof fabric buffing wheels which 10 wheels may carry composition for the dressing, grinding, polishing and giving color to metal. The higher speed hereunder possible for such wheels is a factor for increased buffing rigidity for notwithstanding the rise in 15 temperature dangers from ignition are reduced.

Referring to the drawings:

Fig. 1 is a side view of a fabric disc built up buffing wheel section of this fire-proof 20 loaded material;

Fig. 2 is an enlarged detail view showing the character of the buffing edge before use;

Fig. 3 is a view similar to Fig. 2 showing the edge or fray from use;

Fig. 4 is a side elevation of the buffing disk of the same material as in Fig. 1 as to warp and woof independently of impregnation loading or fire-proofing;

Fig. 5 is an enlarged detail view of a portion of the frayed edge of Fig. 4 as unused;

Fig. 6 is a view of the disk of Fig. 4, after use;

Fig. 7 is a view of an enlarged portion of the disc of Fig. 6, showing the fray after use;

Fig. 8 is a side view of an assembled buffing jack with a plurality of sections of Fig. 1 assembled thereon and set up for high speed use; and

Fig. 9 is a view in side elevation of a 40 stitched buffing section illustrating how the buffing wheel may be further stiffened to a desired extent by stitching, there being used in this instance both the criss-cross as well as the spiral stitching in the event it is desired to have either one supplement the other.

Ply 1 is shown as comprising warp and woof threads. These plies are assembled by stitching 2 about central opening 3 to build up a section 4. These sections 4 of the plies 50 1 are staggered relatively to each other or

angularly shifted as to the warp and woof as assembled into wheel 5 on shaft 6 as clamped in position by nut 7. This shaft 6 is mounted in bearings 8 and is driven by pulley 9. Brackets 10 carry this shaft 6 on pedestal 11. 55

In the carrying out of this invention, applicant takes this warp and woof cotton stock or canvas and subjects it to a saturated solution of aluminum sulphate. After thus thoroughly soaked, the material is dried in an 60

oven at approximately 80° C. Thereafter it is boiled for fifteen minutes in a saturated solution of magnesium carbonate. This dried material has undergone a gain in weight due to this loading by the fireproofing material, 65

but this gain in weight is not to an extent to promote brittleness, say as by forming incrustations on the surface of the material of the plies. Furthermore, it lacks the flexibility 70

which the material had before such treatment, while there is still retained such measure of flexibility that work to be treated as thrust into position at the periphery of the rotating wheel at normal polishing pressures may be partially embedded in such wheel periphery 75

as the work is undergoing the cutting or polishing action. By thus or otherwise building up the ignition point at which this fabric may tend to burn, the allowable frictional heat, due to operation, is increased materially 80

permitting greater wheel speed, and even a greater cutting or effective treatment rate independently of increase in speed, due to the impregnation. This greater speed combined with the greater loading weight of the buffer 85

gives the buffing wheel a greater radial rigidity for standing out against the work as forced thereinto even though the buffer be of what may be termed the loose or unstitched 90

type having merely the central assembly stitching 2. Accordingly, there may be a greater range for temperature coloring of the metal treated. The high speed of operation means a greater quantity or output in a less time reducing the factory overhead as well as the production cost. The wheel, due to its general open structure, may have the composition worked thereinto very readily. The mass of the individual plies, due to this 95 perceptible weight increase on account of 100

the loading, co-operates under greater speed of rotation for a proportional increase in momentum according to the velocity. There is thus imparted a greater uniform peripheral 5 rigidity as to render the wheel exceptionally effective in operation. As herein disclosed the fireproofing treatment of fabric has brought into the buffering art a material advance, not only as to economies directly in the 10 buffering wheel efficiency in lieu of former current practices and even at such lineal speeds and working pressures. However, these attributes of value are believed to be peculiar to the fireproofing as the results are beyond 15 mere bleaching. The wheel has a peripheral softness for thrusting into the work, but still a cutting effectiveness for efficient clearing out and finishing depressions and difficultly accessible regions in the work. The manufac- 20 turing economies have even extended into permitting omissions of steps in preparation for and finishing operations, an instance of which is in annealed brass surfaces bearing scale, where heretofore it has been necessary to 25 rough grind to remove the scale and then polish for thereafter plating, while hereunder this buff is effective for scale removal and plating surface preparation.

The treatment for the fireproofing, as here- 30 in disclosed, is of the fabric after having been woven and seals the warp as to the woof against fraying even at the initial cutting as shown in Fig. 2, and supplements such holding even under the resistance of work opera- 35 tions to a degree for the used buffer (Fig. 3) for approximately less fray even than the un-impregnated similar material buffer of Figs. 4, 5, while the unimpregnated buff as under- going like work conditions has a greatly in- 40 creased fray showing of Figs. 6, 7. It, ac- cordingly, follows that this impregnation in loading buffers permits high speed of opera- tion with generation of greater friction be- cause of the fireproofing and with additional- 45 ly, due to the fireproofing, a greater stiffness as well as a greater weight effecting a more safe holding action so that there is in effect a substantial buffering wheel independently of clamping, stitching or other assembly. Al- 50 though if stitching of a type or combined types as criss-cross, spiral alone, or such com- bined is desired such may be more open than for a similar rigidity non-fireproofed buffer wheel.

55 What is claimed and it is desired to secure by United States Letters Patent is:

A buffering wheel section comprising warp and woof fabric disk-shaped independent plies of fireproofing impregnated material of 60 increased mass with such absence of surface incrustations from the impregnations as to still retain peripheral flexibility for partially embedding work thereinto in normal work treatment, and assembly means for uniting 65 the plies in parallel in a unit of circular form

with warp and woof of adjacent plies staggered, the section being peripherally loose for receiving application of polishing composition thereinto during use rotation alternately with permitting partial embedding of work 70 peripherally into the buffering wheel of said sections while said sections away from said work are maintained in approximately cir- cular form resistant to fraying and ignition and with cutting speed and work pressure 75 capacity above that of such material not thus treated, and thereby lengthening the service and improving the operation thereof.

In witness whereof I affix my signature.
